HEEL SEAT FITTING MACHINES

Antonio P. Charron, Nashua, N. H., assignor to United Shoe Machinery Corporation, Flemington, N. J., a corporation of New Jersey

Application February 7, 1955, Serial No. 486,474

14 Claims. (Cl. 12—31.5)

This invention relates to heel seat fitting machines for preparing the attached outsoles of shoes for the reception of wood heels and is directed to an improvement of a heel seat fitting machine of the type disclosed in application Serial No. 485,844, filed February 3, 1955, in the names of Ferman N. Lee and Harold G. Shaw.

In the use of the heel seat fitting machine which is disclosed in said application Serial No. 485,844 and is an improvement on the machine disclosed in United States Letters Patent No. 1,980,371, granted November 13, 1934 on an application filed in the name of Earl A. Bessom, there is a tendency for the forward median part of the heel seat portion of an attached outsole of a shoe being operated upon to be "bulged" too far through an opening in a horizontal crease plate and below a bottom crease plate face which borders said opening and along which a tab forming knife slides. Consequently, forward portions of lateral bevels of a heel seat tab formed upon the attached outsole of the shoe by the use of said machine sometimes diverge rather than converge as they approach a heel breast line of the outsole and tend to hold the forward part of the heel, which is to be attached to the shoe, from being moved to its proper position for attachment.

In order to insure that the forward portions of the lateral bevels of the heel seat tabs shall converge as they approach the heel breast line of the outsole irrespective of the thickness or temper of the outsole, I have provided an improved crease plate and bulger which is hereinafter described and may be effectively used in the machine disclosed in said application Serial No. 485,844 or in various other heel seat fitting machines in which the heel seat portion of the outsole is deformed at the time it is trimmed for the reception of a heel.

The present invention consists in the novel features hereinafter described, reference being had to the accompanying drawings which illustrate one embodiment of the invention selected for purposes of illustration, said invention being fully disclosed in the following description and claims.

In the accompanying drawings,

Fig. 1 is a front view, partly broken away, of the heel seat fitting machine disclosed in application Serial No. 485,844 equipped with a crease plate and a bulger embodying the present invention and adapted to prepare attached outsoles of shoes for the reception of Louis heels;

Fig. 2 shows a portion of the illustrative machine, partly in side elevation and partly in section, on the line II—II of Fig. 1;

Fig. 3 is a perspective view showing in detail the crease plate and the bulger of the machine shown in Figs. 1 and 2;

Fig. 4 is a perspective view similar to Fig. 3 but showing a crease plate and a bulger which may be used in place of the crease plate and the bulger respectively in Fig. 3 for fitting the heel seat portions of attached outsoles of the shoe for the reception of Cuban heels;

2

Fig. 5 is a vertical median section through the crease plate and the bulger of the machine on the line V—V of Fig. 8 and shows the heel seat portion of the outsole of the shoe, which is to receive a Louis heel, deformed preparatory to forming on the outsole a heel seat tab by the use of a knife which travels along a bottom face of the crease plate;

Fig. 6 is a view on the line VI—VI of Fig. 5;

Fig. 7 is a view on the line VII—VII of Fig. 5 showing the outsole of the shoe after it has been fitted and before the shoe has been removed from the machine;

Fig. 8 is a view on the line VIII—VIII of Fig. 6;

Figs. 9 and 9^a are illustrative views showing respectively in plan halves of Louis and Cuban crease plates in the positions they occupy in the machine and also showing mechanism which supports and guides shoulder forming knives of the machine set to accommodate respectively Louis and Cuban work;

Figs. 10 and 11 are views showing in perspective the rear ends of shoes the heel seats of which have been fitted respectively for the reception of Louis and Cuban heels by the use of the illustrative machine.

The illustrative machine is described with reference to fitting the heel seat portions 29 of attached outsoles 22 of shoes 24 for the reception of Louis heels 26 (Fig. 10) or Cuban heels 26^a (Fig. 11), and comprises Louis or Cuban crease plates 30, 30^a which may be used interchangeably in the machine and upon which the heel seat portions of outsoles are positioned, Louis or Cuban bulgers 32, 32^a which may be used interchangeably in the machine with associated Louis or Cuban crease plates and are adapted to force the heel seat portions of outsoles upon the crease plates through openings 34, 34^a in said plates and below planar or flat surfaces 36, 36^a of the plates, Louis or Cuban back knives 38, 38^a which are interchangeably used in the machine with associated Louis or Cuban crease plates and bulgers and are movable forward along the planar faces of the crease plates to form heel seat tabs 40, 40^a on the heel seat portions of the outsoles, and knives 42 which are moved inward from opposite sides of the outsoles along heel breast lines 44, 44^a thereof to form heel breast receiving shoulders 46, 46^a on the outsoles at the forward ends of said heel seat tabs.

The machine, except for the crease plates 30, 30^a and the bulgers 32, 32^a, is identical with the machine disclosed in the above mentioned application Serial No. 485,844 which may be referred to for a detailed description of the machine and its operation and which is an improvement on the machine disclosed in said United States Patent No. 1,980,371. The machine, as illustrated, is equipped with the Louis crease plate 30, the Louis bulger 32 and the Louis back knife 38. Three different Louis and Cuban crease plates 30, 30^a, which have openings 34, 34^a of different sizes, and three different Louis and Cuban bulgers 32, 32^a adapted for use with associated crease plates, are used interchangeably in the machine to accommodate "runs" of sizes of shoes for the reception of Louis and Cuban heels 26, 26^a.

Any one of the crease plates 30, 30^a may be readily inserted in and removed from guideways 48 (Figs. 1, 2, and 8) formed in a main frame 50 of the machine, the particular crease plate selected for use in the machine being retained in the guideways by a pin 52 which fits slidably in aligned bores 54, 56 formed in the main frame and the crease plate respectively. The back knives 38, 38^a which are used to equip the machine for operating upon Louis and Cuban work respectively have straight and incurved cutting edges 58, 58^a. The shoulder forming knives 42 are used in operating upon both Cuban and Louis work, said knives adjusted for operation upon

Louis work being so mounted that straight vertically arranged cutting edges 60 (Figs. 1 and 2) thereof move along front or breast edges 62 of the crease plate 30 in a vertical plane including a horizontal line 64 (Figs. 6, 7, and 9) which may be referred to as a fixed Louis heel breast line of the machine. The cutting edges 60 of the knives 42, adjusted for operation upon Cuban work, are mounted for movement in horizontal paths 66 (Fig. 9a) which extend along the front or breast edges 62a of the Cuban crease plate 30a positioned in the machine and which are generally tangent to adjacent portions of a fixed Cuban heel breast line 70 of the machine which line lies in a horizontal plane and has a radius equal to the radius of transverse curvature of the forward edge of the attaching face of the Cuban heel 26a. When any one of the Louis crease plates 30 is secured in its operating position in the machine its breast edges 62 lie approximately in the heel breast line 64 which is disposed at right angles to a vertical median plane 72 of the crease plate and also to a vertical median plane 74 of the outsole 22 of the shoe 24 positioned in the machine, which median plane 74 is substantially coincident with the median plane 72. When one of the Cuban crease plates 30a is secured in its operating position in the machine its breast edges 62a are disposed obliquely to a vertical median plane 72a of the crease plate.

The back or tab forming knife 38 is secured to a knife holder 76 screwed to a laterally projecting flange 78 of a slide 80 which is power reciprocated in a constant path along a guideway 82 formed in the main frame 50 in response to the engagement of a one-revolution clutch (not shown) actuated by a treadle (not shown).

The bulgers 32, 32a have formed in them bores 84, 84a for receiving a stud portion 86 of a carrier rod 88 vertically reciprocated in a sleeve 90 which is slideable along a bore 92 of the main frame 50. Mounted on the carrier rod 88 is a cylindrical housing 94 including a spring 96 which has its upper and lower ends bearing against the housing and the top of the sleeve 90. Threaded onto the carrier rod 88 is a nut 98 which limits upward movement of the housing 94 upon the carrier rod. The sleeve 90 floats upon the carrier rod 88 and in the prior machine, disclosed in detail in said Patent No. 1,980,371, has mounted on it a holdown clamp which is not used in the present machine. Downward movement of the carrier rod 88 and accordingly downward movement of the bulger 32 is limited by the engagement of the housing 94 with a shoulder 100 of the main frame 50, the machine being initially adjusted so that the bulger may be lowered to a position in which its lower end is arranged just above the planar face 36 of the crease plate 30. Each of the bulgers 32, 32a is held upon the stud portion 86 of the carrier rod 88 by a spring-pressed plunger 102 and is prevented from turning on said stud portion by inter-engaging shoulders.

The operator presents the shoe bottom up and heel end foremost to the machine causing the rand crease of the shoe to be occupied by portions of one of the crease plates 30, 30a positioned in the machine, the heel seat portion 20 of the attached outsole 22 of the shoe assuming a position over dished outsole supporting faces 103, 103a of the crease plates. As the shoe 24 is moved rearward to its operating position by the operator it is first located widthwise by a V-shaped gage 104 which is engaged by the lateral margins of the rear end of the shoe and which slides rearward toward a back gage 106 under pressure of the shoe. After the rear end of the shoe 24 engages the back gage 106 the gage 104 is moved rearward together with the back gage under pressure until a block 108, which forms part of a unit operatively connected to the back gage, engages a spiral cam initially set in accordance with the length of the attaching face of the heel which is to be received by the shoe and is measured in a heel gage (not shown).

The shoulder forming knives 42 are secured by screws

114 to knife carriers 116 slideable along T-shaped rectilinear guideways 118 (Figs. 2, 9, and 9a) which are formed in guide blocks 120 pivotally mounted on bosses 122 formed on a plate 124 secured to the main frame 50. Formed at the upper ends of the knife carriers 116 are racks 126 meshing with gear segments on levers 128 mounted on shoulder screws 130 threaded into the guide blocks 120. The plate 124 may be considered part of the main frame 50. The bell crank levers 128 are operatively connected by mechanism comprising rods 132, a slide 134, a lever 136, a multipart rod 138 and a universal coupling 140 to a longitudinal lever 142 (Figs. 1 and 2) which is pivotally mounted upon a bearing pin 144 secured to the main frame 50. The shoulder forming knives 42 are constantly urged toward retracted or open positions by the above described mechanism which is biased by a spring 146 (Fig. 1), movement of the knives away from the vertical median plane 72 of the crease plate 30 being limited by the engagement of a stop screw 148 mounted upon the lever 142 with an adjustable stop bar 150. The knife carriers 116 are moved equal distances toward each other along the T-shaped guideways 118 in response to rearward movement of the knife slide 80 which carries a cam roll 152 adapted to depress, during movement of the slide 80 to its retracted position shown in Fig. 2, a cam (not shown) mounted upon the lever 142 whereby to effect inward movement of the carriers 116 and accordingly movement of the shoulder forming knives 42 toward one another to form the heel breast receiving shoulders 46, 46a.

In order to insure that the cutting edges 58, 58a of the tab forming knives 38, 38a shall not be deflected by the work away from the planar faces 36, 36a along which they slide during the tab forming operation, the crease plates 30, 30a are provided with elongated guideways 157, 157a in which the knives fit slidably.

It is difficult to form consistently on outsoles 22 of different thicknesses heel seat tabs 40, 40a having at their forward lateral margins fillets or wings 156, 156a which, in the finished shoes, overlie the upper breast corners of the heels 26, 26a of the shoes 24 and effectively support the rear lateral margins of the shanks of the outsoles of the shoes against drooping or sagging away from the uppers of said shoes. Furthermore, as noted above, in forming heel seat tabs having fillets or wings at their forward lateral margins, there is a tendency to force the forward median parts of the heel seat portions of the outsoles too far below the planar faces 36, 36a of the crease plates 30, 30a with the result that instead of producing, at the forward ends of the tabs 40, 40a forward lateral bevels 158, 158a which converge, as shown in Figs. 7, 10, and 11, there is a tendency for said bevels to diverge as they extend forwardly of the shoes. Many shoes have outsoles which are reinforced along the longitudinal median portions of their shanks by steel shank stiffeners (not shown) and unless the forward ends of the bevels 158, 158a converge, as above explained, there is some likelihood that the fitted heel seat portions of the shoes will hold the front end portions of the rims of the attaching faces of the heels away from the overlasted counter portions of the shoe uppers with the result that the heels are not properly seated upon the shoes. Furthermore, when too much material is left at the forward central portion of the heel seat tab so as to leave a "high spot" at said forward central portion there is a tendency for the heel to be split when it is attached to the shoe.

With the foregoing considerations in view the crease plate openings 34, 34a which extend through and to the front or breast edges 62, 62a of the Louis and Cuban crease plates 30, 30a respectively comprise relatively narrow rear U-shaped portions defined by U-shaped edges 170, 170a and relatively wide entrant portions 172, 172a which extend across the front ends of and laterally beyond opposite sides of the U-shaped openings and terminate at the front or breast edges 62, 62a. Rear lateral margins

of the entrant portions 172, 172^a of the openings 34, 34^a are defined by edges 174, 174^a which extend laterally outward and rearward from the forward ends of the U-shaped edges 170, 170^a and form with forward end portions of said U-shaped edge outsole supporting fingers 176, 176^a extending generally lengthwise of the crease plates 30, 30^a and the openings and separating forward ends of the U-shaped portions of the openings from the rear lateral margins of the entrant portions of the openings. The fingers 176, 176^a are spaced from and are arranged in the vicinity of the front or breast edges 62, 62^a of the crease plates 30, 30^a and may be described as terminating substantial distances rearward of said front or breast edges and as being interposed between median portions of the openings 34, 34^a and lateral portions respectively of said openings.

The Louis and Cuban bulgers 32, 32^a comprise salient median presser portions 178, 178^a which are elongated and U-shaped and which have forward lateral margins or side walls 180, 180^a, and salient lateral presser portions 182, 182^a having inner lateral margins or side walls 184, 184^a which are spaced respectively from the lateral margins or side walls 180, 180^a of the median presser portion and form therewith channels 186, 186^a extending generally length wise of the bulgers. The median presser portions 178, 178^a of the Louis and Cuban bulgers 32, 32^a have flat U-shaped salient faces 182, 188^a, which extend substantially the lengths of the openings 34, 34^a, and the salient lateral presser portions 182, 182^a have flat salient faces 190, 190^a which lie substantially in a plane of said U-shaped salient faces respectively and are of triangular outline. The lateral presser portions 182, 182^a of the bulgers 32, 32^a have front margins extending generally along breast edges or ends 192, 192^a of the bulgers 32, 32^a and have outer margins 194, 194^a arranged generally parallel to opposing portions of the lateral side walls of the entrance portions 172, 172^a of the openings 34, 34^a. Stepped back from the flat faces 190, 190^a of the bulgers 32, 32^a and offset laterally outward from the outer margins 194, 194^a of the lateral presser portions 182, 182^a are clamping faces 195, 195^a which, during the outsole deforming operation, force the forward lateral margins of the heel seat portion of the outsole against forwardly tapered faces 197, 197^a of the crease plates 30, 30^a.

Although the supporting fingers 176, 176^a of the crease plates 30, 30^a have been described as extending generally lengthwise of the crease plates it will be noted that said fingers converge slightly as they extend forward and may be so defined. It will also be noted that the forward lateral margins 180, 180^a of the U-shaped or median presser portions 178, 178^a of the bulgers 32, 32^a converge slightly as they approach the breast edges or ends 192, 192^a of the bulgers and the inner lateral margins or walls 184, 184^a of the lateral presser portions 182, 182^a of the bulgers also converge substantially as they approach the breast edges or ends of the bulger and accordingly the channels 186, 186^a, formed between the lateral margins or walls of the median and the lateral presser portions of the bulgers, may be described as converging as they extend forward or toward the breast edges or faces of the bulgers.

In the operation of the machine which will be described as adapted to accommodate Louis work the operator, after positioning the shoe 24 in the machine with the heel seat portion 20 of the attached outsole 22 of the shoe 24 overlying the crease plate 30 positioned in the machine, depresses the above-mentioned treadle (not shown) causing the carrier rod 88 to be manually depressed and accordingly the bulger 32 to be lowered vertically and at right angles to the planar face 36 of the crease plate to cause the median and lateral presser portions 178, 182 of the bulger to force the median and the forward lateral portions of the heel seat portion of the outsole through the opening 34 and below the planar face 36 of the crease plate and also to cause said presser portions of the bulger to bend adjacent portions of the heel seat portion of the outsole around the fingers 176 as best shown in Figs. 6

and 8 thereby forming at the flesh side of said heel seat portion longitudinally extending creases 196 which converge slightly as they extend forwardly along the outsole. In order to facilitate bending the outsole 22 around the fingers 176 of the crease plate 30, said plate is provided with grooves 198 which extend forward and downward from the outsole supporting face 103 to the planar face 36 of the crease plate. The crease plate 30^a is provided with corresponding grooves 198^a.

When the operator, after viewing the deformed heel seat portion 20 of the attached outsole 22 of the shoe 24, has ascertained that the work is properly positioned and deformed in the machine the treadle (not shown) is further depressed with the result that the above-mentioned one-revolution clutch (not shown) is tripped thereby causing power actuated mechanism to effect further slight depression of the carrier rod 88 and accordingly the bulger 32 until the clamp faces 195 of the bulger 32 force the heel seat portion of the outsole under heavy pressure against the faces 197 of the crease plate and thereafter to effect movement of the knife 38 along the face 36 of the crease plate 30 to form upon the heel seat portion of the outsole 22 the heel seat tab 40 which has at its forward lateral margins the holdown fillets 156. As the tab forming knife 38 is moved rearward the cam roll 152 on the slide 80 which operates the knife 38 engages a cam (not shown) mounted upon the lever 142 causing the shoulder forming knives 42 to be moved inward from the opposite sides of the outsole against the action of the spring 146 to form the heel breast receiving shoulders 46. The operator then removes his foot from the treadle and removes the work from the machine.

The operation of the machine adapted to accommodate Cuban work is the same as above explained, the crease plate 30^a, the bulger 32^a, and the knife 38^a being substituted respectively in the machine for the crease plate 30, the bulger 32, and the knife 38. In operating upon Louis work the T-shaped guideways 118 of the guide blocks 120 are in alignment and are disposed at right angles to the vertical median plane 72 as shown in Fig. 9 whereas in operating upon Cuban work the guideways 118 are disposed at oblique angles to the plane 72^a as shown in Fig. 9a.

During the outsole deforming operation the outer margins 194, 194^a of the lateral presser portions 182, 182^a of the bulgers 32, 32^a and the lateral edges of the entrant portions 172, 172^a of the openings 34, 34^a are spaced by distances less than the thickness of the outsole and pinch between them the outsole with crushing action and serve firmly to hold said outsole against displacement during the forming of the heel seat tab.

Having thus described my invention, what I claim as new and desire to secure by Letters Patent of the United States is:

1. In a heel seat fitting machine, a crease plate having breast edges and having an opening extending through it and to its breast edges and having fingers which extend generally lengthwise of the plate and terminate short of said breast edges and which are interposed between a median portion of the opening and lateral portions respectively of said opening.

2. In a heel seat fitting machine, a crease plate having breast edges and having extending thicknesswise through it and to said breast edges an opening comprising a rear U-shaped portion, which is defined by a U-shaped edge, and a forward entrant portion, rear lateral margins of said entrant portion of the opening being defined by edges which extend laterally outward and rearward away from the forward ends of said U-shaped edge and then forward toward one of said breast edges.

3. In a heel seat fitting machine, a crease plate which has breast edges and has extending thicknesswise through it and to said breast edges an opening comprising a rear U-shaped portion which is defined by a U-shaped edge and is spaced a substantial distance rearward of the

breast edges, and a forward entrant portion which extends to said breast edges and across the forward end of and laterally beyond opposite sides of said U-shaped portion, rear lateral margins of the entrant portion of said opening being defined by edges which extend laterally outward and rearward from forward ends of said U-shaped edge and which form with forward end portions of the U-shaped edge fingers separating a forward end of said U-shaped portion of the opening from the rear lateral margins of the entrant portion of the opening.

4. In a heel seat fitting machine, a crease plate which has breast edges and has extending thicknesswise through it and to said breast edges an opening comprising a rear U-shaped portion defined by a U-shaped edge and a forward entrant portion and which has fingers extending generally lengthwise of said opening, said fingers having inner edges which define respectively the forward portions of said U-shaped edge and having outer edges which defines inner portions of the rear lateral margins of said entrant portion.

5. In a heel seat fitting machine, a crease plate which has breast edges and has extending through it and to its breast edges an opening comprising relatively wide and narrow entrant and inner portions respectively, said crease plate being provided with a pair of fingers which define a portion of said opening and are spaced respectively from opposite sides of the entrant portion of the opening, terminate substantial distances rearward of the breast edges of the crease plate and separate a forward end of the inner portion of the opening from rear lateral margins of the entrant portion of said opening.

6. In a heel seat fitting machine, a crease plate which has breast edges and has extending through and to its breast edges, an opening comprising relatively wide and narrow entrant and inner portions respectively and which has a face bordering said opening, said crease plate comprising a pair of fingers which define a portion of said opening and are spaced respectively from opposite sides of the entrant portion of the opening, terminate substantial distances rearward of the breast edges of the crease plate and separate a forward end of the inner portion of the opening from rear lateral margins of the entrant portion of said opening, a bulger having a median presser portion and lateral presser portions which are spaced from and form with said median presser portion channels which extend generally lengthwise of the bulger, and means for moving the bulger toward the crease plate to cause said median and lateral presser portions of the bulger to force respectively median and lateral margins of the heel seat portion of an outsole through said opening of the crease plate and beyond said face of the plate and to cooperate with said fingers of the crease plate in flexing thicknesswise adjacent portions of the outsole arranged between the portions of the outsole engaged by said median and lateral presser portions of the bulger.

7. In a heel seat fitting machine, a crease plate which has breast edges and has extending thicknesswise through it and to its breast edges an opening and which has a planar face bordering said opening and has a pair of fingers which separate median and marginal portions of the opening from one another and terminate short of said breast edges, a bulger having spaced median and lateral presser portions forming channels between them, means for moving the bulger toward the crease plate at right angles to said planar face to cause the median and lateral presser portions of the bulger to force median and lateral portions of the heel seat portion of an outsole on said plate through said planar face of the crease plate and to cause said presser portions of the bulger to bend intermediate portions of the heel seat portion of the outsole thicknesswise around said fingers to form longitudinally extending creases in the outsole, a tab forming knife having a cutting edge, and means for

moving the knife along said planar face of the crease plate to form upon the heel seat portion of the outsole a heel seat tab having at its forward lateral margins a pair of hold-down fillets.

5 8. In a heel seat fitting machine, a crease plate which has front edges and has extending thicknesswise through it and to its front edges an opening having a rear relatively narrow U-shaped portion and a forward relatively wide entrant portion and which has dished outsole supporting and planar knife engaging faces bordering said opening and a pair of fingers which extend generally longitudinally of the crease plate but converge slightly as they extend forward of the crease plate and which separate a forward end of the U-shaped portion of the opening from rear lateral margins of the entrant portion of the opening, a bulger having a median presser portion having a length equal to the length of said opening and having lateral presser portions which are spaced from a forward portion of said median presser portion and form therewith channels which extend slightly inward as they extend forward, means for moving the bulger relatively to the crease plate at right angles to said planar knife engaging face to cause median and forward lateral portions of a heel seat portion of an outsole upon the crease plate to be forced through the opening and below the knife engaging face of the crease plate and to cause intermediate portions of the heel seat portion of the outsole to be wrapped around and supported by said fingers, a knife movable along said planar face of the crease plate to form on the outsole a heel seat tab having hold-down wings at its forward lateral margins, and means for forming heel breast receiving shoulders on the outsole.

35 9. In a heel seat fitting machine, a crease plate which has breast edges and has extending through it and to said breast edges an opening and which has a planar face bordering said opening and a pair of fingers which extend generally lengthwise of the crease plate and are spaced from but are arranged in close proximity to the breast edges of the plate and are interposed between a median portion of the opening and lateral portions respectively of said opening, a bulger having a median presser portion and lateral presser portions which are spaced from opposite sides of said median presser portion and form channels therewith, means for moving the bulger at right angles to said planar face of the crease plate to force said median and lateral presser portions of the bulger against an outsole on a shoe supported by the crease plate to project a median portion and lateral portions of the outsole through the opening and beyond said planar face of the crease plate and also to cause intermediate portions of the outsole to be wrapped around said fingers of the crease plate, a knife, and means for moving the knife along said planar face of the crease plate to form a heel seat tab.

10. In a heel seat fitting machine, a crease plate which has breast edges and has extending through it and to its breast edges an opening and which has a planar face bordering said opening and a pair of forwardly extending fingers which separate median and lateral portions respectively of the opening and terminate substantial distances from the breast edges of said opening, a bulger comprising a median presser portion having forwardly converging side walls and lateral presser portions which have forwardly converging side walls opposing and spaced from the side walls of the median presser portion and forming channels therewith, means for moving the bulger at right angles to said planar face of the crease plate to force the median and lateral presser portions of the bulger into the median and the lateral portions of the opening whereby to force the median and lateral portions of a heel seat portion of an outsole upon said crease plate through the median and lateral portions of the opening and beyond said planar face of the crease plate and to cause the side walls of said presser portions to bend

parts of the heel seat portion of the outsole around said supporting fingers, a tab forming knife having a cutting edge, and means for moving the cutting edge of the knife along said planar face to form upon the deformed heel seat portion of the outsole a heel seat tab having at its forward lateral margins a pair of holdown fillets.

11. In a heel seat fitting machine, a crease plate which has breast edges and has extending through and to its breast edges an opening comprising a rear relatively narrow U-shaped portion and a forward relatively wide entrant portion and which has outsole supporting and planar knife engaging faces bordering the opening and a pair of longitudinal forwardly converging supporting fingers which are arranged between a forward portion of said U-shaped opening and rear lateral margins of said entrant portion of the opening, a bulger having a salient median presser portion comprising a flat U-shaped face extending substantially the length of the opening of the crease plate and a pair of salient forward lateral presser portions comprising flat salient faces which lie substantially in a plane of said U-shaped face, are of triangular outline and are spaced from said median salient face, said median and lateral presser portions forming between them a pair of longitudinally extending forwardly converging channels, means for moving the bulger toward the crease plate at right angles to the planar knife engaging face of the crease plate to force median and forward lateral portions of a heel seat portion of an outsole through the opening and beyond said planar face of the crease plate and to bend adjacent portions of the heel seat portion of the outsole around said fingers, a knife movable along said planar face of the crease plate to form on the heel seat portion of the outsole a heel seat tab having at its forward lateral margins laterally extending holdown wings, and means for forming heel breast re-

10

ceiving shoulders on the outsole at the forward end of said tab.

12. In a heel seat fitting machine, a bulger comprising a rigid salient median presser portion having lateral margins and rigid salient lateral presser portions which are positively connected to said median presser portion and have inner lateral margins which are spaced from the lateral margins of the median presser portion and form therewith channels extending generally lengthwise of the bulger.

13. In a heel seat fitting machine, a bulger comprising a salient U-shaped presser portion having lateral margins and a breast edge and having salient lateral presser portions which are spaced from and are arranged at opposite sides of the breast edge portion of the salient U-shaped presser portion and have inner lateral margins which form with the lateral margins of said salient U-shaped presser portion channels extending generally lengthwise of the bulger.

14. In a heel seat fitting machine, a bulger comprising a median U-shaped presser portion having a breast edge and having forward lateral margins which converge as they approach said breast edge and triangular salient lateral presser portions which are spaced from and are arranged at opposite sides of a forward portion of the U-shaped presser member and have inner lateral margins which form with the lateral margins of the U-shaped presser member channels extending generally lengthwise of the bulger but converging as they approach said breast edge of the bulger.
